UNITED STATES PATENT OFFICE

156,612

FENDER ORNAMENT

John L. Domann and John A. Domann,
South Gate, Calif.

Application June 10, 1949, Serial No. 3,174

Term of patent 3½ years

(Cl. D48—32)

To all whom it may concern:

Be it known that we, John L. Domann and John A. Domann, citizens of the United States of America, residing at South Gate, county of Los Angeles, State of California, have invented a new, original, and ornamental Design for a Fender Ornament, of which the following is a specification, reference being had to the accompanying drawings, forming a part thereof:

Figure 1 is a perspective view of a fender ornament showing our new design.

Figure 2 is a side elevational view.

Figure 3 is an end elevational view.

The dotted lines showing the lens are for illustrative purposes only.

We claim:

The ornamental design for a fender ornament, substantially as shown and described.

JOHN L. DOMANN.
JOHN A. DOMANN.
